JOINED STRUCTURE

Lawrence D. Morton, Sandusky, Ohio, assignor to
The Hinde and Dauch Paper Company

Application October 30, 1934, Serial No. 750,665

6 Claims. (Cl. 229—48)

The aim of this invention is to provide a joining means and jointed structure particularly suitable for employment with sheets of corrugated board, or other sheet-like materials of sufficient thickness to be butt-joined at their edges. The particular advantage of this invention with corrugated board is that by a suitable joint board can be made into greater widths than is possible on machines at present in use, and although not strictly unitary, will be as rigid and firm in construction as though it were actually a single piece.

For various mechanical reasons it is standard practice in the fiber board industry to limit sheets to an extreme width of sixty inches. Machines for making greater widths are not desirable to build and operate, either from an engineering or manufacturing standpoint. This limitation has considerably restricted the use of fiber board as a packaging material for large objects. Joints hitherto devised for such boards have been structurally weak and generally so unsatisfactory that the packaging industry has made little or no effort to use fiber board where a dimension of more than sixty inches in width for a single surface is necessary.

Although the invention is shown and described as directed to joining corrugated boards in the direction of their width, this is done because it is the most desirable use for the invention, however the joint would be equally applicable to connecting lengths, but is seldom so used because corrugated board is generally manufactured by a continuous process in the direction of its length. Hence, in making packages, display panels, and fiber board structures generally, size limitations are due to the width of the material.

Besides enabling corrugated board to be used in greater widths than hitherto possible, my invention also permits the utilization of trimmings and narrow remnants which would otherwise be useless. Consequently although the use which has so far been made of my invention indicates that its principal advantage is in the making of large boxes and box-like structures for packaging or display, it is by no means limited to large sizes.

In particular, the invention accomplishes its purpose by a joint construction such that, especially in a structure having angularly-related walls, sliding of the abutting edges with respect to one another, and lifting of the edges out of their common plane, are both prevented. Thus the joint is one which can neither move

sideways nor overlap its ends, and is at least as strong as the material joined.

To the accomplishment of the foregoing and related ends, said invention, then, consists of the means hereinafter fully described and particularly pointed out in the claims.

The annexed drawing and the following description set forth in detail certain structure embodying the invention, such disclosed means constituting, however, but one of various structural forms in which the principle of the invention may be used.

In the accompanying drawing Fig. 1 illustrates an unfinished conventional carton embodying my invention; Fig. 2 represents the completed carton, both views being in perspective; Fig. 3 is a detail in plan of my improved joint, with parts broken away to show the construction; Fig. 4 is a cross section on the line 4—4, Fig. 3; and Fig. 5 is a view similar to Fig. 3 but showing a modified form.

Two different forms of joint are shown, but it is to be understood that these are illustrative of the principle and that other shapes suitable for the purpose may be employed. Only one jointed structure is illustrated, as a typical and preferred embodiment. Any number of sections may be so joined.

In the carton of Figs. 1 and 2, the top and bottom pieces of board 11 and 12 are joined so as to give an overall extension greater than would be the case if a single piece were used. This may be regarded either as illustrative of a carton more than sixty inches high, and thus necessitating the employment of a wider stock than hitherto deemed practical, or of a box made of board pieces, perhaps edges from some other operation, which are too narrow in themselves to give the necessary height.

The sheets to be joined, designated by the reference characters 11 and 12 in Figs. 1 to 4 inclusive and 11' and 12' in Fig. 5, have the edges which are to be brought into abutment cut in a corresponding pattern, as for example the angular teeth 13 and 14, with corresponding indentations 15 and 16. In making the joint these edges are brought into engagement edge to edge, either with or without adhesive. These edges so brought together as shown in Fig. 3 are held in place and reenforced, preferably on each side, by a heavy strip of suitable material such as stout paper, cloth or the like, ordinarily fastened with adhesive. Mechanical fasteners might be employed, but are not shown, not being generally used. Such strips are in-

dicated by the reference characters 17 and 18. Preferably this reenforcing tape will be of a width somewhat greater than that of the teeth so as to overlap the entire joint and hold on each side, as at 20.

In a box or box-like structure embodying my invention the toothed parts are mutually interlocking so that the chief function of the tape or other fastening means is to prevent the sections from pulling apart. The teeth on each face prevent the upper and lower parts of that face from moving sideways upon one another, and for this reason also lock the upper and lower parts of the adjacent faces against moving out of their common plane.

By way of illustration, let A and B designate the faces visible in Fig. 1, and let the double-headed arrows *a* and *b* designate the directions of displacing tendency. Obviously the teeth of face A prevent movement in either direction of arrow *b*, consequently not only preventing side-slip between the two parts of A but also keeping the two parts of B in the same plane. And of course in like manner the teeth of B are a lock against relative movement of the parts of A.

This principle is clearly not limited to a prismatic structure, but is equally applicable to cylinders, to tubes of elliptical or irregular transverse section and in general to any bodies wherein certain of the teeth are so disposed with reference to others that movement of certain teeth in and out of abutment is prevented by side engagement of others.

Although best, it is not essential to the practice of the invention that the edges match closely.

In the modified form shown in Fig. 3 the abutting edges are scalloped with interengaging rounded projections 13' and recesses 14', brought together either with or without adhesive, and fastened with tape 17 and 18 as in Fig. 3.

From the foregoing it will be seen that I have invented a joint which, while particularly adapted for use with corrugated board is also suitable for use with other materials whose characteristics adapt themselves for such treatment, including solid fiber boards, thin wooden sheets either single or multi-ply, and so on.

Besides the advantage that the joining means of each side of the box prevents the other side from moving out of abutting relation, my improved structure also has the advantage that the strains which tend to break the joint, either by bending, or by a hinging action at one end of a side joint, or by stresses in shear, all tend to be widely distributed, thus avoiding any con-

centration at any one point. As a consequence, a structure built up by the use of joints of the type herein disclosed is fully as strong at the joint as at any other part and, indeed, any stresses to the breaking point result in a failure 5 elsewhere than at the joint, before the joint gives way.

Other modes of applying the principle of my invention may be employed instead of the one explained, change being made as regards the 10 structure herein disclosed, provided the means stated by any of the following claims or the equivalent of such stated means be employed.

I therefore particularly point out and distinctly claim as my invention:

1. A joint for abutting edges of pieces of flat material having at least two angularly related faces, said joint comprising irregularities on the end of each piece, said irregularities being adapted to interengage to prevent side movement between the pieces on one face and simultaneously to prevent movement of the pieces out of abutment on the other face.

2. A box of inherently stiff sheet material comprising portions, each of said portions having an open end, said open ends being complementarily shaped to prevent side motion in any direction when abutting.

3. A box of inherently stiff sheet material comprising portions each of dimensions substantially up to the commercial size limits of such sheets, each of said portions having an open end, said open ends being complementarily shaped to prevent side motion in any direction when abutting.

4. A box of inherently stiff sheet material comprising at least two portions adapted for endwise engagement and not lying entirely in one plane and teeth on the abutting ends of said portions.

5. A built-up structure of inherently stiff sheet material, comprising sections having abutting ends, interengageable teeth on said ends, certain of said teeth being substantially transverse to others, whereby the side engagement 40 of abutting teeth prevents movement of other teeth out of abutment.

6. A built-up structure of inherently stiff sheet material, comprising sections having abutting ends, interengageable teeth on said ends, certain of said teeth being substantially transverse 50 to others, whereby the side engagement of abutting teeth prevents movement of other teeth out of abutment, and connecting means between adjacent sections preventing longitudinal separation 55 of the sections.

LAWRENCE D. MORTON.

CERTIFICATE OF CORRECTION.

Patent No. 2,027,747.

January 14, 1936.

LAWRENCE D. MORTON.

It is hereby certified that error appears in the above numbered patent requiring correction as follows: In the drawing, Figure 1 should appear as shown below instead of as shown in the patent -

and that the said Letters Patent should be read with this correction therein that the same may conform to the record of the case in the Patent Office.

Signed and sealed this 7th day of April, A. D. 1936.

Leslie Frazer
(Seal) Acting Commissioner of Patents.
